UNITED STATES PATENT OFFICE.

EDISON E. RANDALL, OF KANKAKEE, ILLINOIS, ASSIGNEE, BY MESNE ASSIGNMENTS,
TO POPE MACHINE COMPANY, OF KANKAKEE, ILLINOIS, A CORPORATION OF
ILLINOIS.

MACHINE FOR UNITING LOOPED FABRICS.

Application filed February 27, 1922. Serial No. 539,700.

To all whom it may concern:

Be it known that I, EDISON E. RANDALL, a citizen of the United States, residing at Kankakee, in the county of Kankakee and State of Illinois, have invented certain new and useful Improvements in Machines for Unitting Looped Fabrics, of which the following is a specification, reference being had therein to the accompanying drawing.

10 This invention primarily relates to machines for uniting looped fabrics, and it has especial reference to machines for sewing together the edges of knitted goods or looped fabrics such as stockings and the like.

The structure constituting my inventive-concept is particularly designed for use in association with a continuously operated mechanism for raising a line of stitching 20 into the operative zone of a thread-severing or cutting device, such as is disclosed in my United States Letters Patent No. 1,205,107, granted November 14, 1916. As explained in that patent, it is desirable to sever the 25 stitching thread which extends from one article to the next where the articles are impaled upon pins circularly arranged on a rotatable support or dial forming a component of a hosiery looping machine. In 30 practice, it has been found that as a line or chain of stitches produced by the stitch-forming mechanism of the machine is advanced by the traveling pin-carrying support, it is important that such line or chain 35 shall be directed as nearly as may be into the field of movement of the stitch-raising instrumentality in order to insure engagement thereby to feed the same to the cutting device. The present invention is predicated upon the discovery that by developing 40 a pressure upon the chain or line of stitching as the same rests upon the impaling pins, such chain or line will be given a normal tendency to curl upwardly and, 45 thus, be raised into a plane above that of the pins and into a position to insure its engagement by the thread-raising and severing mechanisms.

It is evident that this inventive-concept 50 may be carried into effect by various types of structures; but as a result of considerable experiment and practical operation, I have found that that which is herein disclosed has features of advantage and is exceedingly efficient for the purpose. It will

therefore be understood that, in showing in the accompanying drawings a form of structure adapted for the purpose mentioned, such drawings are merely illustrative and intended to exemplify a practical type of device; but it is to be noted that the illustrated device is susceptible of a wide range of variation and modification without departing from the salient features and underlying principles of the invention; and it is also to be observed that the invention may likewise be differently embodied.

In these drawings:

Figure 1 is a view in top plan of a looping machine with my invention embodied therein;

Fig. 2 is a view in sectional elevation, on the line 2—2, Fig. 1, showing on an enlarged scale my improved thread-curling device;

Fig. 3 is a similar view from the opposite side;

Fig. 4 is a fragmentary view, in rear elevation, (partly in section), of my improved thread-curling device;

Fig. 5 is a fragmentary view in top plan and on an enlarged scale showing particularly the action of a chain-guiding component forming part of the curling device; and

Fig. 6 is a view in perspective of the curling device and its thread-guiding component detached.

It is deemed unessential here to detail the construction and operation of a machine for sewing looped fabrics, inasmuch as such a structure is well known in the art. It will here suffice to explain that such a machine includes a base 1 that is, as usual, secured to a suitable table or bench (not shown) and in which machine is journaled a main driving shaft 2 from which the various mechanisms of the machine are operated and to which power is supplied through a suitable pulley 3. An outwardly-projecting overhanging arm 4 rises from the base 1 and has depending therefrom, at its outer end, a stud 5 to which is rigidly secured a ring form or support 6. A ring or dial 7 is rotatably mounted upon the ring support and given a continuous rotary movement by a worm gear, designated generally by the reference-character 8 (Fig. 1) operated by the main shaft 2, all in a well-known manner.

The ring 7 carries a series of impaling pins or points 9, of usual form, construction and dimensions, and projecting radially from the ring. These pins are of sufficient length to hold the meshes or loops of the edges of a given article, such as a stocking, which are to be united, and the operator places the articles at various distances apart successively upon these impaling pins, leaving a more or less irregular portion projecting thereabove.

A trimming mechanism, indicated at 10 and operated from an eccentric 11 secured to a worm shaft 12 actuated from the main shaft 2 through a pinion 13 which meshes with a bevel-gear 14 fast on the shaft 2, automatically trims off the upwardly-projecting edges of the article, leaving only a sufficient portion projecting above the impaling pins to be caught and united by stitch-forming mechanism, designated generally by the reference-character 15.

In the construction illustrated, the impaling pins rotate in a clockwise direction as viewed in Fig. 1, and each article on the impaling pins, after it passes the trimming mechanism 10, is brought into the field of action of the stitch-forming mechanism 15, which places a line of stitching in the projecting edges of the article then impaled upon the pins and immediately above such pins. The threads carried by the stitch-forming mechanism extend continuously from one impaled article to another and just above the plane of the pins. As the pin-supporting ring 7 rotates, it carries each article from the stitch-forming mechanism toward a stitch or thread cutting mechanism associated with the pin ring 7, and in the drawings designated generally by the reference-character 16, and which is supported, at a predetermined distance from the stitch-forming mechanism, upon any suitable portion of the machine and operated in any suitable way. In this instance, however, I prefer to operate the cutting mechanism continuously from the continuously-rotating worm shaft 12, all as described in my aforementioned Patent No. 1,205,107. Here, as there, the cutting mechanism is supported upon a bracket 17 which, preferably and as shown, extends radially outward. For convenience, this outwardly-projecting bracket is made in two parts 18 and 19, respectively, held together by screws 20. The part 18 is formed with an integral transversely-extending lug or bearing 21.

The cutting mechanism includes two relatively movable shearing blades 22 and 23, the field of action of which is preferably located above the line of stitching, indicated at 23, above the impaling pins: In this instance, means are provided for raising or lifting the thread extending from the

stitched portion above the line of stitching into the field of action of the cutting mechanism. In the preferred form of construction here illustrated, this result is secured by the inner, fixed shearing blade 23 extending down close to the impaling pins upon the welt 24, while the movable or pivoted cooperating shearing blade 22 moves back and forth above the line of stitching 25, and in conjunction therewith there is employed a thread-lifter 26 which moves intermittently with the movable shearing blade 22 toward and from the fixed blade 23. The lifter 26 is of sufficient length to contact with the projecting welt 24, and is restrained in its movement thereby; but as the stitched article advances, this lifter, being unrestrained by the welt 24, passes beneath the thread 25 and in its continued movement lifts this thread upwardly into the field of action of the shearing blades.

The movable shearing blade 22 is pivotally mounted by being secured to a shaft 27 mounted in the bearing 21. This shearing blade, at its cutting or effective edge, is shorter than the fixed blade 23, so that as it swings back and forth, it passes above the line of stitching and the welt and, hence, the field of action of the cutting mechanism is at all times above the welt. Movement of the shearing blade is effected by rocking the shaft 27, this being effected through the linkage 28 connected to the shaft and to an eccentric 29 secured to and operated by the worm shaft 12.

The thread lifter 26 is pivoted on the shaft 27, and is of such length that, in its movement, it passes close above the impaling pins and contacts with the welt 24. It is yieldingly held against the movable blade 22 by a contractile spring 30 and derives its motion by reason of its relation to that blade.

Operation: The operation of the cutting mechanism, so far described, will be apparent: After the fabric on the impaling pins has been trimmed off by the trimming mechanism 10, and stitched by the stitching mechanism 15, thereby forming the slightly projecting stitched portion or welt 24, it advances toward and past the cutting mechanism. Inasmuch as the stitched portion or welt 24 projects immediately in front of the lower edge of the fixed shearing blade 23, the action of the movable blade 22 will be in a plane above the welt, while the lifter 26 will strike against the welt and be thereby restrained against the action of the spring 30. This action continues until the welt or stitched portion has passed out from the path of the lifter 26, whereupon, at the next inward swing of this lifter, there being no stitched portion or welt to restrain its movement, the lifter continues its movement and passes beneath the projecting thread 25 and

past the fixed blade 23, thus lifting the thread upwardly upon its inclined edge 31 into the field of action of the cutting mechanism. As the edge of the movable cutting 5 blade follows immediately after the projecting point of the lifter, the thread is at once severed. The cutting mechanism continues to operate and sever any projecting end of the stitched chain 25 until the next impaled 10 article is reached, when its welt will pass into the path of the lifter and restrain it and prevent a further cutting operation. Thus, it will be seen that, owing to the position of the lifter with respect to the cutting 15 blades, the projecting ends of the thread or stitched chain are severed at substantially equal and uniform distances from the finished article because the point at which the thread shall be severed is determined by the stitched portion of the article 20 itself.

To insure the raising of the stitched chain 25 to the inclined edge 31 of the lifter so that the latter will function to present 25 the same to the cutting mechanism, as above described, I have combined with the lifter, as a companion device thereto, a thread or chain curling device designated, generally, by the reference-character 32: This device 30 comprises a bell-crank-lever 33 operating on an axis comprising the screw 34 and having an outstanding portion 35. Attached to a stud 36 on the lever 33 is a spring 37 which, at its opposite end, is connected to 35 a stud 38 secured in the bracket member 19. Adjustably mounted on the outstanding portion 35 of the lever 33 is a curling member 39 provided with a short slot 40 through which extends a headed screw 41. The slot 40 and screw permit adjustment of the curling member on the supporting portion of the lever 33. The curling member is formed with an angulated thread-engaging portion 42, slightly inclined to the vertical, and 45 having its lower face comparatively smooth or polished.

Loosely pivoted, as on a screw 43, is a chain-guiding member 44, shorter in length than the lever 33 and having a beveled 50 thread-engaging end 45 normally occupying a position intermediate the edges of the thread-engaging portion 42.

Operation: As the line of stitching or chain 25 travels with the pin-carrier, the 55 curling member 39 normally exerts a pressure upon the underlying chain, such that the latter is caused to curl upwardly so that its end will have a normal tendency to direct itself toward the beveled edge 31 of 60 the thread lifter 26, with the result that this chain is, thus, automatically brought into position for action by the lifter 26 to raise the same into position for the severing action of the cutting blades. It will be understood, of course, that after a hosiery ar-

ticle has passed beyond the cutting mechanism, a predetermined length of the chain 25 is left uncut. As soon as the cutting mechanism becomes active, the free end of the chain—then being without any support—70 would naturally fall toward the pins 9; but by reason of the action of the member 42 on the chain, the latter is caused to have an upward curling movement until just before its rear end reaches the cutting mechanism, and at which point the cutting mechanism ceases to act upon the chain. It may be explained that this operation, as here set forth, is that which is clearly observable 75 and it is assumed that the drawing of the 80 chain along the under surface of the curling portion 42 produces a sort of twisting or curling action on the chain, the extent of which is predetermined by the strength of the spring 37, the latter being the instrumentality which rocks the lever 33 on its axis 34 and holds the curling device 39, with its curling portion 42 in contact with the pins 9.

To insure the constant positioning of the 90 chain or line of stitching under the curling portion 42, the chain is guided by the beveled portion 45 of the member 44, the latter sliding over the pins 9 by reason of the fact that it is loosely supported on the lever 95 33 by the screw 43. Where two hosiery articles are relatively close together on the impaling pins, the chain 25 between these two articles would ordinarily be maintained in a position to register with the curling 100 portion 42; but if the chain 25 be of considerable length by reason of the two hosiery articles being spaced far apart—as shown, for instance, in Fig. 5—this chain 105 would then be at a considerable angle to the curling device and would not always be in a position to be acted upon by the curling device. The member 44 operates constantly to hold the chain so that it will be guided directly to and beneath the curling portion 110 42.

From the foregoing, it will be understood that, after a chain or line of stitches has been formed by the mechanism 15, those 115 portions of the chain which extend between impaled articles will be guided by the member 44 to the curling device which, then, becomes active to effect the curling of the chain, which gives it a tendency to position itself into the zone of action of the thread lifter 26, whereupon the cutting mechanism operates to sever it in a manner already explained.

What I claim is:

1. A machine for sewing looped fabrics, 125 including a movable impaling pin support, impaling pins arranged thereon and traveling therewith, stitch-forming mechanism for securing together the impaled fabric loops by forming a line or chain of stitches there-

in and above the impaling pins, continuously-operated chain raising and severing mechanism juxtaposed to the path of travel of the pins, and a chain-curling device associated with said mechanism.

2. A machine for sewing looped fabrics, including a movable impaling pin support, impaling pins arranged thereon and traveling therewith, stitch-forming mechanism for 10 securing together the impaled fabric loops by forming a line or chain of stitches therein and above the impaling pins, continuously-operated chain raising and severing mechanism juxtaposed to the path of travel of the pins, and a chain-curling device associated with said mechanism and overlying the pins.

3. A machine for sewing looped fabrics, including a movable impaling pin support, impaling pins arranged thereon and traveling therewith, stitch-forming mechanism for 20 securing together the impaled fabric loops by forming a line or chain of stitches therein and above the impaling pins, continuously-operated chain raising and severing mechanism juxtaposed to the path of travel of the pins, and a chain-curling device associated with said mechanism and overlying the pins and comprising a pin-engaging element.

4. A machine for sewing looped fabrics, 30 including a movable impaling pin support, impaling pins arranged thereon and traveling therewith, stitch-forming mechanism for securing together the impaled fabric loops by forming a line or chain of stitches therein and above the impaling pins, continuously-operated chain raising and severing mechanism juxtaposed to the path of travel of the pins, and a chain-curling device associated with said mechanism and overlying the pins and comprising a pin-engaging element and means for causing the element to have a normal tendency to effect pressure on the chain.

5. A machine for sewing looped fabrics, 40 including a movable impaling pin support, impaling pins arranged thereon and traveling therewith, stitch-forming mechanism for securing together the impaled fabric loops by forming a line or chain of stitches therein and above the impaling pins, continuously-operated chain raising and severing mechanism juxtaposed to the path of travel of the pins, and a chain-curling device associated with said mechanism and overlying the pins and comprising a pin-engaging element and means for causing the element to have a normal tendency to effect pressure on the chain and consisting of a resilient member connected to the element.

6. A machine for sewing looped fabrics, 50 including a movable impaling pin support, impaling pins arranged thereon and traveling therewith, stitch-forming mechanism for securing together the impaled fabric loops by forming a line or chain of stitches therein

and above the impaling pins, continuously-operated chain raising and severing mechanism juxtaposed to the path of travel of the pins, and a chain-curling device associated with said mechanism and overlying the pins, 70 and comprising a bell-crank member and a spring to effect a normal pressure of the member against the pins.

7. A machine for sewing looped fabrics, 75 including a movable impaling-pin-support, stitch-forming mechanism juxtaposed to the path of travel of the support for securing the edges of fabric impaled on the support and operating to form a chain of stitches above the same, chain-severing mechanism 80 juxtaposed to the path of travel of the pin support, and comprising a movable cutter and a relatively stationary cutter, and a chain-engaging device comprising a pair of oppositely-disposed upper and lower surfaces, the upper surface being substantially arc-shaped to raise the chain toward the central section of the stationary cutter and into a plane above that of the lower edge thereof.

8. A machine for sewing looped fabrics, 90 including a movable impaling-pin-support, impaling pins thereon and traveling therewith, stitch-forming mechanism for securing the edges of fabric impaled on the pins and operating to form a chain of stitches above the pins, chain-severing mechanism 95 juxtaposed to the path of travel of the pins and comprising a movable cutter and a relatively stationary cutter, a chain-engaging device comprising a pair of upper and lower arc-shaped surfaces oppositely disposed, the upper surface operating to raise the chain into a plane above that of the lower edge of the stationary cutter, and resilient means 100 for controlling the device.

9. A machine for sewing looped fabrics, 110 including a movable impaling pin support, impaling pins thereon and traveling therewith, stitch-forming mechanism for securing the edges of fabric impaled on the pins and operating to form a chain of stitches above the pins, a chain-severing mechanism juxtaposed to the path of travel of the pins, and a chain-curling device adapted to produce within the chain a disturbed relation 115 between the parts thereof, so as to cause the chain to curl, and thereby direct the chain into the operating zone of the severing mechanism.

10. A machine for sewing looped fabrics, 120 including a movable impaling pin support, impaling pins thereon and traveling therewith, stitch-forming mechanism for securing the edges of fabric impaled on the pins and operating to form a chain of stitches above the pins, a chain-severing mechanism juxtaposed to the path of travel of the pins, a chain-curling device adapted to produce within the chain a disturbed relation be- 125 130

- between the parts thereof, so as to cause the chain to curl, and thereby direct the chain into the operating zone of the severing mechanism, and a thread-guiding member associated with the chain-curling device. 70
11. A machine for sewing looped fabrics, including a movable impaling pin support, impaling pins thereon and traveling therewith, stitch-forming mechanism for securing the edges of fabric impaled on the pins and operating to form a chain of stitches above the pins, a chain-severing mechanism juxtaposed to the path of travel of the pins, a chain-curling device having a normal tendency to curl the chain and thereby direct the chain into the operating zone of the severing mechanism, and a thread-guiding member associated with the chain-curling device and slideable over the pins. 75
- 10 12. A machine for sewing looped fabrics, including a movable impaling pin support, impaling pins thereon and traveling therewith, stitch-forming mechanism for securing the edges of fabric impaled on the pins and operating to form a chain of stitches above the pins, a chain-severing mechanism juxtaposed to the path of travel of the pins, a chain-curling device having a normal tendency to curl the chain and thereby direct the chain into the operating zone of the severing mechanism, and a thread-guiding member associated with and tracking the chain-curling device as the latter rides over the pins. 80
- 15 13. In combination, a thread-severing mechanism operable upon a chain of stitches produced in a looper machine, and a thread-curling device associated with said mechanism and having a normal tendency to produce within the chain a disturbed relation between its parts, so as to cause the chain to curl, and thereby direct the chain into the operating zone of the severing mechanism. 85
- 20 14. In combination, a thread-severing mechanism operable upon a chain of stitches produced in a looper machine, and a thread-curling device associated with said mechanism and having a normal tendency to produce within the chain a disturbed relation between its parts, so as to cause the chain to curl, and thereby direct the chain into the operating zone of the severing mechanism, and comprising a pin-engaging member and a pressure-producing element operating thereon. 90
- 25 15. In combination, a support, a thread-severing mechanism thereon, and a thread-curling device also on the support operable to produce within a chain of stitches presentable to the thread-severing mechanism a disturbed relation between the parts of the chain, so as to cause such chain to curl, and thereby direct the chain into the operating zone of the severing mechanism. 95
- 30 16. In combination, a support, a thread-severing mechanism thereon, a thread-curling device also on the support operable to produce within a chain of stitches presentable to a thread-severing mechanism a disturbed relation between the parts of the chain, so as to cause such chain to curl, and thereby direct the chain into the operating zone of the severing mechanism, and a thread-guiding member associated with the curling device. 100
- 35 17. In combination, a support, a thread-severing mechanism thereon, a thread-curling device also on the support operable to produce within a chain of stitches presentable to a thread-severing mechanism a disturbed relation between the parts of the chain, so as to cause such chain to curl, and thereby direct the chain into the operating zone of the severing mechanism, and a thread-guiding member associated with the curling device and movable independently thereof. 105
- 40 18. In combination, a support, a thread-severing mechanism thereon, a thread-curling device also on the support operable to produce within a chain of stitches presentable to a thread-severing mechanism a disturbed relation between the parts of the chain, so as to cause such chain to curl, and thereby direct the chain into the operating zone of the severing mechanism, and a thread-guiding member associated with the curling device and movable independently thereof. 110
- 45 19. A machine for securing the edges of looped fabrics, including a movable pin support, impaling pins thereon and traveling therewith, stitch-forming mechanism operating to produce a series or chain of stitches over the pins, a thread-severing device juxtaposed to the path of travel of the pins, and a chain-guiding and positioning device, freely movable vertically, normally resting by gravity upon and riding over the pins, and active on the chain in advance of the operation thereon of the severing device. 115
- 50 20. A machine for securing the edges of looped fabrics, including a movable pin support, impaling pins thereon and traveling therewith, stitch-forming mechanism operating to produce a series or chain of stitches over the pins, a thread-severing device juxtaposed to the path of travel of the pins, and a chain-guiding and positioning device, freely movable vertically, normally resting by gravity upon and riding over the pins, and active on the chain in advance of the operation thereon of the severing device for locating the chain in the zone of action of the severing device, the guiding device tracking the severing device as the pins travel under the same. 120
- 55 21. A machine for sewing the edges of looped fabrics, including a support, a pivoted member thereon having an approximately flat thread-engaging portion, and a spring connected to the member and support to cause the thread-engaging portion 125
- 60 16. In combination, a support, a thread- 130

- to have a normal tendency to bear downwardly.
22. A machine for sewing the edges of looped fabrics, including a support, a pivoted bell-crank member thereon having an approximately flat thread-engaging portion, and a spring connected to the member and support to cause the thread-engaging portion to have a normal tendency to bear 10 downwardly.
23. A machine for sewing the edges of looped fabrics, including a support, a pivoted member thereon having an approximately flat thread-engaging portion adjustable on the member, and a spring connected to the member and support to cause the thread-engaging portion to have a normal tendency to bear downwardly.
24. A machine for uniting looped fabrics, including a movable impaling pin support, impaling pins arranged thereon and traveling therewith, stitch-forming mechanism for securing together the impaled fabric loops, thread-severing mechanism juxtaposed to the path of travel of the pins, and a thread-curling device associated therewith and adapted to produce within a chain presentable to the severing mechanism a disturbed relation between the parts of the chain, so as to cause it to curl, and thereby direct such chain into the operating zone of the severing mechanism.
25. A machine for uniting looped fabrics, including a movable impaling pin support, impaling pins thereon, stitch-forming mechanism associated with the support for forming a line of stitching above the impaling pins, mechanism acting to raise a line of thread formed by the stitch-forming mechanism, and a curling device juxtaposed to the thread-raising mechanism.
26. A machine for uniting looped fabrics, including a movable impaling pin support, impaling pins thereon, stitch-forming mechanism associated with the support for forming a line of stitching above the impaling pins, mechanism acting to raise a line of thread formed by the stitch-forming mechanism, and a curling device juxtaposed to the thread-raising mechanism, and comprising a thread-engaging member and means having a normal tendency to press the same toward the pins while bearing upon the line of stitching formed above the pins.
27. A machine for uniting knit fabric, including a movable impaling pin support, impaling pins thereon, stitch-forming mechanism associated with the support for forming a line of stitching above the impaling pins, mechanism for severing the line of stitching, and a curling device associated with the severing mechanism and functioning to produce within the line of stitching a disturbed relation between its components 65 so as to cause such line to curl and thereby

to give it a normal tendency to rise away from the pins.

28. A machine for uniting knit fabric, including a movable impaling pin support, impaling pins thereon, stitch-forming mechanism associated with the support for forming a line of stitching above the impaling pins, mechanism for severing the line of stitching, and a curling device associated with the severing mechanism and functioning to produce within the line of stitching a disturbed relation between its components so as to cause such line to curl and thereby to give it a normal tendency to rise away from the pins and comprising a line-engaging member, means for causing the member to have a normal tendency to press against the pins and the line of stitching over the same, and a guide disposed at one side of the member for guiding the line of stitching thereto.

29. A machine for uniting knit fabric, including a movable impaling pin support, impaling pins thereon, stitch-forming mechanism associated with the support for forming a line of stitching above the impaling pins, mechanism for severing the line of stitching, and a curling device associated with the severing mechanism and functioning to produce within the line of stitching a disturbed relation between its components so as to cause such line to curl and thereby to give it a normal tendency to rise away from the pins and comprising a line-engaging member and means for causing the member to have a normal tendency to press against the pins and the line of stitching over the same.

30. As an article of manufacture, a bracket, stitch raising and severing mechanism mounted thereon, and a curling device also mounted on the bracket and operative with the stitch raising and severing mechanism.

31. A machine for sewing looped fabrics, including a movable impaling pin support, impaling pins thereon, stitch-forming mechanism for securing together the impaled portions of the fabric by forming a line of stitching thereon above the impaling pins, continuously-operated mechanism acting to raise the thread extending from the stitched portion above the line where the stitching is formed and then to sever the same thread, and a curling device juxtaposed to the thread-severing mechanism and comprising a thread-engaging member, a resilient element holding the member in operative relation with respect to the support, and a bracket on which the member swings.

In testimony whereof I affix my signature in presence of two witnesses.

EDISON E. RANDALL.
